CABLE CAR PLAY HOUSE

Lyle A. Johnson, Los Altos, Calif., assignor to San
Francisco Chronicle, San Francisco, Calif.

Filed Dec. 16, 1960, Ser. No. 63,233

Term of patent 14 years

(Cl. D34—15)

Fig. 1.

Fig. 2.

Fig. 3.

Fig. 4.

Fig. 5.

FIG. 1 is a perspective view of a cable car play house showing my new design;

FIG. 2 is a side elevational view, with the opposite side being substantially a mirror image thereof;

FIG. 3 is an end elevational view viewed from either end of the design shown in FIG. 1;

FIG. 4 is a top plan view thereof; and

FIG. 5 is a bottom plan view thereof.

The characteristic features of my design reside in the combination of a play house comprising a quadrangular box having rakish trapezoidal walls and a roof top with sloping sides having a shallow rectangular ventilator effect in the central portion thereof, the whole suggesting a cable car, all as shown.

I claim:

The ornamental design for a cable car play house, as shown and described.
